UNITED STATES PATENT OFFICE.

ALBERT FOURNIER, OF CHICAGO, ILLINOIS.

METHOD OF MAKING ORNAMENTAL STRUCTURES.

1,072,712.

Specification of Letters Patent.

Patented Sept. 9, 1913.

Application filed October 19, 1911. Serial No. 655,591.

To all whom it may concern:

Be it known that I, ALBERT FOURNIER, a citizen of the United States, residing at Chicago, in the county of Cook and State 5 of Illinois, have invented a new and useful Method of Making Ornamental Structures, of which the following is a specification.

My invention relates to the art of securing together sections of material to produce an 10 ornamental design; and, more particularly, to the art of manufacturing ornamental structures, such as, for example, windows, panels, globes, and the like, vases, urns and the like, and ornamental surfacings for 15 buildings.

The kind of ornamental surfacings above referred to, and to which my invention relates, are such as are used on the surfaces of building structures for ornamenting the 20 same and involving the provision of a bed or foundation to which the ornamental sections, as for example, glass, metal, marble or stone of such colors and shapes as to produce the surfacings of a desired design, are 25 secured.

My primary objects, generally stated, are to reduce the cost, and facilitate the manufacture, of the structures above referred to; and, as regards the manufacture of ornamental surfacings, to provide for the securing 30 of the sections of ornamental material to the bed or foundation by means which will insure the retention of the said sections in the bed.

Referring to the accompanying drawings, in which I have illustrated the manner of producing, in accordance with my invention, a flat plate of ornamental surfacing for application to a surface to be ornamented—Figure 1 shows a face view of a flat plate of ornamental surfacing constructed in accordance with my invention. Fig. 2 is a section taken at the line 2 on Fig. 1, and viewed in the direction of the arrow. Fig. 3 is a face view of a portion of the mold used in the production of the plate of Fig. 1, showing two of the sections of ornamental material which form the ornamental design applied in the proper position to the mold preparatory to the molding operation. Fig. 4 is a section taken at the line 4 on Fig. 3 and viewed in the direction of the arrow; and Fig. 5, a section taken through the mold, ornamental-sections and the molded material, at a line corresponding to the line 4 on Fig. 3, showing the applica-

tion of the molded material to the rear sides of the ornamental sections in which it extends through the spaces between the adjacent edges of such sections and keys the 60 latter to the body of the molded material.

My invention, as regards my improved method of producing ornamental surfacings of the character above referred to, involves, generally stated, the preparation of a mold 65 having grooves formed in a surface thereof, conforming generally to the skeleton of the design to be produced; applying to the grooved surface of the mold the sections of ornamental material, which are to be exposed to view in the finished article to cause opposing edges thereof to be spaced apart at the grooves and extend part way over the latter; and thereupon applying to the surfaces of said sections material which is susceptible of hardening, to cause it to extend 70 into the spaces between adjacent edges of the sections and into the grooves in the mold to form heads overlapping the marginal edges of the sections on their front sides. 80

To practice, in the preferred manner, the above-stated method for forming ornamental-surfacings in plate form, I provide a mold 6, the side-walls 7 of which extend upwardly from the base and form a mold-cavity 8 of an area and shape corresponding to that of the ornamental plate to be produced, such as that shown in Fig. 1. The mold which may be made of any suitable material, as for example plaster of Paris, 90 has its bottom grooved as represented at 9, these grooves corresponding to the skeleton of the design to be produced and which design it will be understood may be of any configuration. The sections of glass, or other ornamental material which it is desired be used, to form the ornamental surface, of approximate shapes to produce the desired design and which sections are represented at 10, are then placed upon the 100 grooved surface of the mold. The sections 10 should be of such size or sizes as to cause their opposing edges, when the sections 10 are applied to the grooved surface of the mold, to be spaced apart at the grooves 9 to 105 form spaces 11 and extend part way over the adjacent grooves 9 as represented of the two sections 10 illustrated in Fig. 3. The material for securing the sections together, and which forms a base therefor, is then introduced into the mold to cover the rear 110 sides of the sections 10, the material which

is represented at 12, filling the spaces between the sections 10 and filling the grooves 9 all as represented in Fig. 5. Upon becoming set, the material 12, with the sections 10 united thereto, may be removed from the mold, the material 12 forming a backing 13 for the sections 10 and presenting ribs 14 having heads 15 which overlap the marginal edges of the sections 10 on the faces of the latter and form keys which serve to securely lock the sections 10 to the backing 13.

The material 12 may be of any kind which may be introduced into the mold to enter the spaces 11 and the grooves 9, as described, and become set for the purpose stated, a desirable material for my purpose being any kind of cement, though any other suitable material may be used.

20 The above-described method may be utilized in the manufacture of vases, urns, columns, trays and the like structures, the molds for molding such, or similar objects, being formed in sections and conforming, in shape, as is the practice in manufacturing such objects, with the shape of the object to be made. When such molds are used they would be provided on their inner surfaces with grooves 9 as described of the mold 25 illustrated, and the sections 10 of material for ornamenting the exposed surface of the object to be produced would be positioned in the mold-sections as described and preferably temporarily secured thereto, for holding the sections 10 spaced apart with their adjacent edges partway overlapping said grooves and preventing displacement thereof during the molding operation, as by the use of wax (not shown), or other suitable 30 adhesive.

To practise my invention, in the preferred manner, for the manufacture of art-glass windows, panels, globes, and the like, involving the securing together of the glass-sections by means engaging with the marginal edges of said sections, a mold of the character illustrated and described may be employed and the glass sections relatively disposed on the mold, as hereinbefore explained for the forming of the ornamental design. In manufacturing such objects, all but the marginal portions of the ornamental sections thus applied to the mold would preferably be blocked out at their rear sides 50 before the material 12 is introduced into the mold, to cause the material 12, at the rear sides of the sections 10, to lap the marginal edges only thereof, instead of extending over the entire surface; or, if desired, the material 55 12 may be spread over the entire surfaces of the sections 10 exposed in the mold as illustrated in the drawings and hereinbefore described, and thereafter all of the molded material applied to the rear sides of the sections 10, except that which overlies the mar-

ginal portions of these sections at the rear side thereof, removed; or the material 12 may be poured directly into the spaces 11 between the sections 10 and grooves 9 to cause the material 12 to overlap the marginal edges of said sections at opposite sides thereof by pouring the material 12 from a receptacle, in a relatively fine stream, into said spaces 11 and in doing so following the skeleton of the design. The practising of any of the last three described methods produces the overlapping of the material 12 with the marginal edges of the sections at both the front and rear sides thereof, but leaves the major portions of the sections 10 70 75 80 uncovered.

It will be manifest that by my improved method cementitious materials affording varying degrees of smoothness of surface may be used; and thus the ribs 14 may be caused to simulate the appearance of the corresponding part of the object which the design to be produced is copied from, as for example, where the ribs 14 of the finished article represent the trunk or branches of a 90 tree, in which case the cementitious material of a kind producing a relatively rough surface could be used. Furthermore, different colored materials of which the ribs 14 are formed may be used to cause the design produced to closely simulate the object of which it is a copy, and produce harmony in the design, or, if desired, the ribs 14 may be colored, for the purpose stated, as by tinting them. It will also be understood that where 100 the ribs 14 in the finished structure correspond to certain portions of the object which the design is to simulate, as for example the trunk of a tree, the exposed surface of the ribs 14 may be caused to conform to the corresponding surface of the object which in such case would be ribbed and roughened as by so forming the bottom surfaces of the grooves 9 as to cause them to present replicas of the surfaces of those 110 parts of the object which the ribs, molded therein, are to simulate.

What I claim as new, and desire to secure by Letters Patent, is—

1. The method of securing in place sections of material to produce an ornamental design, which includes grooving a mold surface to produce grooves conforming to the skeleton of the design, applying to said surface sections of ornamental material to conform to said skeleton, with opposing edges of said sections spaced apart at the grooves and opposite edges thereof extending partway over the grooves, and introducing into said spaces and therethrough into the grooves material susceptible of hardening for permanently securing said sections in their design-forming relation and forming on the obverse surface ribs following the outline of the design. 115 120 125 130

2. The method of securing in place sections of material to produce an ornamental design, which includes grooving a mold surface to produce grooves conforming to the skeleton of the design and to the marginal surfaces thereof, applying to said surface sections of ornamental material to conform to said skeleton, with opposing edges of said sections spaced apart at the grooves and opposite edges thereof extending part way over the grooves, and applying to the marginal surfaces of said sections, and introducing into said spaces and therethrough into the grooves, material susceptible of hardening for permanently securing said sections in their design-forming relation and forming on the obverse surface ribs following the outline of the design.

3. The method of securing in place sections of material to produce an ornamental

design, which includes grooving a mold surface to produce grooves conforming to the skeleton of the design, applying to said surface sections of ornamental material to conform to said skeleton, with opposing edges 25 of said sections spaced apart at the grooves and opposite edges thereof extending part way over the grooves, and applying to the rear sides of said sections to completely cover the same, and introducing into said 30 spaces and therethrough into the grooves, material susceptible of hardening for permanently securing said sections in their design-forming relation and forming on the obverse surface ribs following the outline of 35 the design.

ALBERT FOURNIER.

In presence of—

JOHN WILSON,

RALPH SCHAEFER.
